UNITED STATES PATENT OFFICE.

RUDOLPH SATTLER, OF CINCINNATI, OHIO, AND LEO J. MORAND, OF COVINGTON, KENTUCKY.

INKING APPARATUS.

1,130,022.

Specification of Letters Patent.

Patented Mar. 2, 1915.

Application filed May 23, 1914. Serial No. 840,435.

To all whom it may concern:

Be it known that we, RUDOLPH SATTLER and LEO J. MORAND, citizens of the United States, and residents of Cincinnati, in the county of Hamilton and State of Ohio, and Covington, in the county of Kenton and State of Kentucky, respectively, have invented certain new and useful Improvements in Inking Apparatus, of which the following is a specification.

Our invention relates to inking apparatus for printing presses, and more especially for embossing presses; and the object is to reduce the waste of ink incident to the wiping of the surface of the embossing die.

Our invention consists in the parts and in the details of construction and arrangement of parts as will hereinafter be more fully described and claimed.

In the drawings: Figure 1 is a sectional diagrammatic illustration of part of an embossing press with our invention applied thereto; Fig. 2 is an enlarged cross section, on the line $x-x$ of Figs. 4 and 5, of a device embodying our invention; Fig. 3 is a further enlarged cross section of the upper part of the blade and of the pressure bar, with the web passing between the blade and pressure bar, and also illustrating how the ink is removed from the web, the thickness of the layer of ink, however, being exaggerated; Fig. 4 is a plan view of the device; and Fig. 5 is a rear elevation of the same.

The press which we have chosen for illustrating the use of our invention has the embossing die 1 reciprocated by a lever 2 through the medium of links 3 and 4, back toward the fountain 5 and forward to the front of the press, not shown, where the impression is made. The fountain 5 has the roller 6 taking up ink 7 from the fountain, with a doctor roller 8 bearing thereon; and a distributing roller 9, suitably carried on an arm 10, takes the ink from the roll 6 and distributes it over the die 1 when the die is back near the fountain. The ink is thus spread over the entire surface of the die and down in the depressions formed by the engraving on the die, such as the depressions 11 therein, but only the ink in the depressions is to be transferred to the work, as is well known in the art of embossing and printing with one impression. Therefore, a means is provided for wiping all of

the ink from the die except that in the depressions 11. On this press, a pad 12 with a tightly stretched surface of suitable fabric 13, such as felt, has a web of paper 14 drawn under it, so that, as the die 1 passes under the pad 12, the upper surface of the die and the lower surface of the web 14 are very tightly pressed together and all of the ink on the plane surface of the die is wiped off onto the web 14. This web of paper 14 is supplied from a roll 15 near the top of the press, which roll is properly retarded by a strap 16 suspended from an arm 17 and held against the roll by the weight 18. The web passes forward and down over suitably arranged rollers to the pad 12 and back under the pad to a roll 19, upon which the paper is wound. The roll 19 is intermittently turned by suitable mechanism, which need not be described, but which comprises the rod 20, making connection with a moving part of the press; and in this manner a new length of the web of paper is brought under the pad 12 at each reciprocation of the die 1, and each new length thus receives a quantity of ink from the plane surface of the die. The web wound on the roll 19 with these quantities of ink thereon becomes waste paper, and of course, whatever ink remains on the web when it is rolled up on the roll 19 is wasted.

The above details of the parts are described to facilitate the understanding of our invention, but it will be understood that any other press with a web wiping the surface ink from the die or form may be provided with our invention.

As here shown in connection with the press above described, brackets 21 and 22 are clamped to a cross bar or strut 23 which this press has at the rear, and these brackets have a blade 24 rigidly fixed to them by screws 25. A pressure bar 26 is hinged to the bracket 21 to drop down over and along the upper edge of the blade 24, and the other bracket 22 has a latch 27 which will hold the pressure bar 26 down along said edge of the blade 24. By means of this hinged mounting the pressure bar 26 may be raised and the web 14 where it passes from the pad 12 up to the roll 20 may be brought under the pressure bar 26 and thus press down against the upper edge of the blade 24, so that the blade may scrape off a large portion of the ink that the web

14 has wiped from the die 1 and is carrying upward toward the roll 20. This ink, thus scraped from the web 14, runs down the forward or inner side of the blade 24, 5 where it is caught by a chute 28 that slants rearwardly and downwardly, so that this ink is thus delivered back to the fountain 5 and thus adapted to be used instead of wasted. It is of course highly desirable 10 to scrape off as large a proportion of this ink from the web as is possible; but it is also necessary to avoid scraping off any of the fiber of the paper of which the web 14 is composed; because such fiber, mingling 15 with this ink and passing back to the fountain will soon adulterate the ink, so that the impressions obtained will be inferior, and may even show the fibers thus present in the ink. Another precaution that is necessary 20 is to carry the web 14 across the edge of the blade 24 without tearing or cutting the web. To avoid these difficulties we provide a flat thin flexible pressure-regulating strip 29 held up against the flat lower 25 side of the pressure bar 26 by screws 29' passing up through the strip at its ends, into the pressure bar, and provide a plurality of adjusting screws 30 passing down through the pressure bar at intervals therealong and bearing against the upper side 30 of the strip. Under this pressure-regulating strip 29 a pad 31 of suitable fabric, such as felt, is interposed; and the lower corners 32 of the pressure bar 26 are rounded, and this pad 31 is stretched from one side of the pressure bar down under the rounded corners 32 and under the lower side of the strip 29 and up to the other side of the pressure bar, being held to the sides of the 40 pressure bar by plates 33 with screws 34 passing through them and through the pad 31 into the sides of the pressure bar. As shown in Fig. 2 we preferably place an additional strip 35 under the strip 29, somewhat forward of the edge of the blade 24, 45 and held also by the screws 29'. This presses the material of the pad 31 and of the web 14 very slightly downward, so that the web must travel upward very slightly 50 to meet the edge of the blade, thereby better facilitating the scraping of the ink from the web.

With the device constructed as just described, and with the pressure-regulating screws 30 at close intervals along the pressure bar 26, and with the pressure-regulating strip 29 moderately flexible, each short interval of length of the edge of the blade 24 may have the web pressed against it with 55 exactly the right pressure to scrape most of the ink from the paper and yet not disturb the fiber of the paper. The pad 31, interposed between the pressure-regulating strip 29 and the edge of the blade, in conjunction 60 with the rounded corners of the pressure bar 26 and with the chamfered edges 29" of the adjusting strip 29, allows the web to pass under and around the pressure bar with the pressure so distributed upon it that it is not cut or torn. The edge of 70 the blade 24 is preferably made somewhat dull, so as not to cut the surface of the web. The blade may be narrowed as indicated by the dotted line A in Fig. 5, if the ink is of such nature that it does not run 75 freely off the wider blade.

The chute has sides 36 with hooks 37 which slip over screws 38 passing into the inner sides of the brackets 21 and 22, so that this chute 28 may be readily removed 80 from the device to allow convenient access to the mechanism of the fountain and ink-distributing means.

After the ink has been distributed on the die and then wiped off and carried up by 85 the web and then recovered by our device, it is generally dried out somewhat and becomes of somewhat thicker consistency. This ink, passing back to the fountain and mingling with the fresh ink therein, will, 90 after some operation of the machine, generally increase the thickness of consistency of the ink in the fountain to an objectionable extent. To compensate for this, we may provide a supply of a suitable thinning liquid, such as turpentine, supplied to the ink in minute quantities. Thus, each 95 of the brackets 21 and 22 may be provided with rearwardly projected lugs 39 at their lower ends, and a bar 40 may be fixed to 100 these lugs 39 by screws 41, which bar 40 may support cups 42 at intervals therealong, with stems 43 extending through the bar 40 to deliver the thinning liquid to the chute 28, there to mingle with the ink that has 105 run down from the blade 24. The cup 42 may have a cut-off 44 to regulate the volume of the liquid delivered, which will generally be set so that the liquid drips very slowly from the cup into the chute, 110 since only a very small quantity of the thinning liquid is generally required to maintain the proper consistency of the ink in the fountain with this recovered ink being delivered back thereto.

As here shown, the brackets 21 and 22 have rearwardly projected pedestals 45 and caps 46 that embrace the bar 23 before alluded to, and the cap 46 being held to the pedestal by screws 47, which, when drawn up, clamp the entire device very rigidly to this bar 23. The device may be clamped to the bar 23 at any suitable angle to receive the web around the under side of the pressure bar 26 in such a manner as to 120 avoid any cutting tendency of the blade 24. Thus, as shown in Fig. 1, the device is tilted forward somewhat, for this reason.

Other means may be employed for attaching the device to the machine parts, espe- 125

cially with presses of construction somewhat different from that used for example herein.

It will be understood that our invention is capable of considerable modification, and therefore we do not wish to be understood as being limited to the details of construction and arrangement herein set forth as an example, but

What we claim as new and desire to secure by Letters Patent is:

- 10 1. In combination with means for making an impression, from which means a portion of ink must be removed before the impression is made, a web, and means for applying successive lengths of web to remove successive portions of ink from the impression-making means, fixed means positively bearing against opposite sides of the web to recover ink therefrom.
- 20 2. In combination with means for making an impression, from which means a portion of ink must be removed before the impression is made, a web, and means for applying successive lengths of the web to remove successive portions of ink from the impression-making means, fixed means positively bearing against opposite sides of the web to recover ink therefrom, and means for positively regulating the action of said recovering means upon said web.
- 30 3. In combination with means for making an impression, from which means a portion of ink must be removed before the impression is made, a web, and means for applying successive lengths of the web to remove successive portions of ink from the impression-making means, means bearing against the web to recover ink therefrom, stationary means flexing and positively supporting the web for the recovering means to bear thereon, and means to minimize the disrupting action of the supporting means on said web.
- 40 4. In combination with means for making an impression, from which means a portion of ink must be removed before the impression is made, a web, and means for applying successive lengths of the web to remove successive portions of ink from the impression-making means, means bearing against the web to recover ink therefrom, means flexing and positively supporting the web for the recovering means to bear thereon, means to minimize the disrupting action of the supporting means on said web, and means to adjust the action of the supporting means in holding the web for the bearing of the recovering means, whereby the removal of the ink is maximized, and the disturbance of the material of the web is minimized.
- 50 5. In combination with means for making an impression, from which means a portion of ink must be removed before the impression is made, a web, and means for applying successive lengths of the web to remove suc-

cessive portions of ink from the impression-making means, means bearing against the web to recover ink therefrom, and a stationary pressure bar flexing and positively supporting the web for the recovering means to bear on the web.

6. In combination with means for making an impression, from which means a portion of ink must be removed before the impression is made, a web, and means for applying successive lengths of the web to remove successive portions of ink from the impression-making means, means bearing against the web to recover ink therefrom, and a pressure bar flexing and positively supporting the web for the recovering means to bear on the web, said pressure bar being hinged, whereby it may release said web from the recovering means.

7. In combination with means for making an impression, from which means a portion of ink must be removed before the impression is made, a web, and means for applying successive lengths of the web to remove successive portions of ink from the impression-making means, means bearing against the web to recover ink therefrom, a pressure bar supporting the web for the recovering means to bear on the web, a flexible pressure-adjusting strip interposed between the pressure bar and the web, and means for variably adjusting different intervals of length of said strip, to variously adjust different intervals of the width of the web where the recovering means bears on the web.

8. In combination with means for making an impression, from which means a portion of ink must be removed before the impression is made, a web, and means for applying successive lengths of the web to remove successive portions of ink from the impression-making means, means bearing against the web to recover ink therefrom, a stationary pressure bar flexing and positively supporting the web for the recovering means to bear on the web, and a part interposed between said pressure bar and said web to minimize the disruptive effect of the pressure bar on the web.

9. In combination with means for making an impression, from which means a portion of ink must be removed before the impression is made, a web, and means for applying successive lengths of the web to remove successive portions of ink from the impression-making means, means bearing against the web to recover ink therefrom, and a stationary pressure bar flexing and positively supporting the web for the recovering means to bear on the web, parts of the pressure bar presented toward the web being convex to minimize the disruptive action of the pressure bar on the web.

10. In combination with means for making an impression, from which means a por-

- tion of ink must be removed before the impression is made, a web, and means for applying successive lengths of the web to remove successive portions of ink from the impression-making means, means bearing against the web to recover ink therefrom, a pressure bar supporting the web for the recovering means to bear on the web, parts of the pressure bar presented toward the web being convex, and a pad interposed between the pressure bar and the web to minimize the disruptive action of the pressure bar on the web.
11. In combination with means for making an impression, from which means a portion of ink must be removed before the impression is made, a web, and means for applying successive lengths of the web to remove successive portions of ink from the impression-making means, means bearing against the web to recover ink therefrom, a pressure bar supporting the web for the recovering means to bear on the web, a flexible pressure-adjusting strip interposed between the pressure bar and the web, and means for variably adjusting different intervals of length of said strip, to variously adjust different intervals of the width of the web where the recovering means bears on the web, parts of the pressure bar and of the adjusting strip presented toward the web being convex to minimize the disruptive action of said pressure bar and said strip on the web.
12. In combination with means for making an impression, from which means a portion of ink must be removed before the impression is made, a web, and means for applying successive lengths of the web to remove successive portions of ink, a blade with an edge bearing against the web to scrape ink therefrom, stationary means flexing and positively supporting the web for the blade to scrape thereon, and means to minimize the disrupting action of the supporting means on said web.
13. In combination with means for making an impression, from which means a portion of ink must be removed before the impression is made, a web, and means for applying successive lengths of the web to remove successive portions of ink, a blade with an edge bearing against the web to scrape ink therefrom, means supporting the web for the blade to scrape thereon, means to minimize the disrupting action of the supporting means on said web, and means to adjust the action of the supporting means in holding the web for the blade to scrape thereon, whereby a maximum proportion of the ink is scraped off the web, and the disturbance of the material of the web by said scraping is minimized.
14. In combination with means for making an impression, from which means a portion of ink must be removed before the impression is made, a web, and means for applying successive lengths of the web to remove successive portions of ink, a blade with an edge bearing against the web to scrape ink therefrom, and a stationary pressure bar flexing and positively supporting the web for the blade to scrape the web.
15. In combination with means for making an impression, from which means a portion of ink must be removed before the impression is made, a web, and means for applying successive lengths of the web to remove successive portions of ink, a blade with an edge bearing against the web to scrape ink therefrom, means supporting the web for the blade to scrape thereon, means to minimize the disrupting action of the supporting means on said web, and means to adjust the action of the supporting means in holding the web for the blade to scrape thereon, whereby a maximum proportion of the ink is scraped off the web, and the disturbance of the material of the web by said scraping is minimized, said supporting means being hinged, whereby it may release said web from said blade.
16. In combination with means for making an impression, from which means a portion of ink must be removed before the impression is made, a web, and means for applying successive lengths of the web to remove successive portions of ink, a blade with an edge bearing against the web to scrape ink therefrom, a pressure bar supporting the web for the blade to scrape on the web, a flexible pressure adjusting strip interposed between the pressure bar and the web, and means for variably adjusting different intervals of the length of said strip to variously adjust different intervals of the width of the web, when said blade scrapes on the web.
17. In combination with means for making an impression, from which means a portion of ink must be removed before the impression is made, a web, and means for applying successive lengths of the web to remove successive portions of ink, a blade with an edge bearing against the web to scrape ink therefrom, means supporting the web for the blade to scrape thereon, means to minimize the disrupting action of the supporting means on said web, means to adjust the action of the supporting means in holding the web for the blade to scrape thereon, whereby a maximum proportion of the ink is scraped off the web, and the disturbance of the material of the web by said scraping is minimized, and a pad interposed between said supporting means and said web to minimize the disruptive effect of the supporting means on the web.
18. In combination with means for making an impression, from which means a portion of ink must be removed before the impression is made, a web, and means for applying successive lengths of the web to remove successive portions of ink, a blade with an edge bearing against the web to scrape ink therefrom, and a stationary pressure bar flexing and positively supporting the web for the blade to scrape the web.

tion of ink must be removed before the impression is made, a web, and means for applying successive lengths of the web to remove successive portions of ink, a blade with 5 an edge bearing against the web to scrape ink therefrom, means supporting the web for the blade to scrape thereon, means to minimize the disrupting action of the supporting means on said web, and means to 10 adjust the action of the supporting means in holding the web for the blade to scrape thereon, whereby a maximum proportion of the ink is scraped off the web, and the disturbance of the material of the web by said 15 scraping is minimized, parts of the supporting means presented toward the web being convex to minimize the disruptive action of the supporting means on the web.

19. In combination with means for making an impression, from which means a portion of ink must be removed before the impression is made, a web, and means for applying successive lengths of the web to remove successive portions of ink, a blade 25 with an edge bearing against the web to scrape ink therefrom, means supporting the web for the blade to scrape thereon, means to minimize the disrupting action of the supporting means on said web, means to 30 adjust the action of the supporting means in holding the web for the blade to scrape thereon, whereby a maximum proportion of the ink is scraped off the web, and the disturbance of the material of the web by said 35 scraping is minimized, parts of the supporting means presented toward the web being convex, and a pad interposed between the supporting means and the web to minimize the disruptive action of the supporting 40 means on the web.

20. In combination with means for making an impression, from which means a portion of ink must be removed before the impression is made, a web, and means for 45 applying successive lengths of the web to remove successive portions of ink, a blade with an edge bearing against the web to scrape ink therefrom, a pressure bar supporting the web for the blade to scrape on 50 the web, a flexible pressure adjusting strip interposed between the pressure bar and the web, and means for variably adjusting different intervals of the length of said strip to variously adjust different intervals of the width of the web, when said blade scrapes on the web, parts of the pressure bar and of the adjusting strip presented toward the web being convex to minimize the disruptive action of said pressure bar and 55 strip on the web.

21. In combination with means for making an impression, from which means a portion of ink must be removed before the impression is made, a web, and means for 60 applying successive lengths of the web to

remove successive portions of ink from the impression-making means, means bearing against the web to recover ink therefrom, a pressure bar supporting the web for the recovering means to bear on the web, a 70 flexible pressure-adjusting strip interposed between the pressure bar and the web, and a plurality of screws passing through the pressure bar against said strip, at intervals along the pressure bar and strip, to variously adjust different intervals of the width of the web when the recovering means bears on the web.

22. Ink recovering means comprising means to bear on a web and remove ink 80 therefrom, and a stationary pressure bar flexing and positively supporting the web for the means to bear thereon.

23. Ink recovering means comprising means to bear on a web and remove ink 85 therefrom, a pressure bar supporting the web for the means to bear thereon, a flexible pressure-adjusting strip interposed between the pressure bar and the web, and means for variably adjusting different intervals of 90 length of said strip to variously adjust different intervals of the width of the web when said means bears on the web to remove the ink therefrom.

24. Ink recovering means comprising 95 means to bear on a web and remove ink therefrom, a pressure bar supporting the web for the means to bear thereon, a flexible pressure-adjusting strip interposed between the pressure bar and the web, and means for 100 variably adjusting different intervals of length of said strip to variously adjust different intervals of the width of the web when said means bears on the web to remove the ink therefrom, parts of the pressure bar and of the adjusting strip presented toward the web being convex, to minimize the disruptive action of said pressure bar and said strip on the web.

25. Ink recovering means comprising 110 means to bear on a web and remove ink therefrom, a stationary pressure bar flexing and positively supporting the web for the means to bear thereon, and a part interposed between said pressure bar and said 115 web to minimize the disruptive effect of the pressure bar on the web.

26. Ink recovering means comprising means to bear on a web and remove ink therefrom, and a stationary pressure bar 120 flexing and positively supporting the web for the means to bear thereon, parts of the pressure bar presented toward the web being rounded to minimize the disruptive action of the pressure bar on the web.

27. Ink recovering means comprising means to bear on a web and remove ink 125 therefrom, and a stationary pressure bar flexing and positively supporting the web for the means to bear thereon, parts of the 130

- pressure bar presented toward the web being convex, and a pad interposed between the pressure bar and the web, to minimize the disruptive action of the pressure bar on the web.
28. Ink recovering means comprising a blade, means for supporting the blade, and a pressure bar hinged to the supporting means to be raised or to be brought down toward an edge of the blade, and means for positively holding the pressure bar down toward the blade.
29. Ink recovering means comprising a blade, means for supporting the blade, and a pressure bar hinged to the supporting means to be raised or to be brought down toward an edge of the blade, means for positively holding the pressure bar down toward the blade, and a chute removably mounted upon the supporting means to catch and deliver ink from said blade.
30. Ink recovering means comprising a blade, means for supporting the blade, and a pressure bar hinged to the supporting means to be raised or to be brought down toward an edge of the blade, means for holding the pressure bar down toward the blade, said supporting means comprising brackets at respective ends of the blade to which the blade is rigidly secured, a pedestal on each bracket, and a cap, and means for securing said cap on the pedestal, each pedestal and its cap being adapted to embrace a fixed part of a machine, and thereby rigidly mount the recovering means on the machine for use on said machine.
31. Ink recovering means comprising a blade, means for supporting the blade, and a pressure bar hinged to the supporting means to be raised or to be brought down toward an edge of the blade, means for holding the pressure bar down toward the blade, said supporting means comprising brackets at respective ends of the blade to which the blade is rigidly secured, a pedestal on each bracket, and a cap, means for securing said cap on the pedestal, each pedestal and its cap being adapted to embrace a fixed part of a machine, and thereby rigidly mount the recovering means on the machine for use on said machine, a projection on the inner side of the lower end of each bracket, and a chute having hooks engaging over the projections, whereby it is held to catch and deliver ink from said blade.
32. In combination with means for making an impression, and means for supplying ink thereto, said impression-making means requiring a portion of the ink to be removed from it before the impression is made, and means for removing this portion of ink, ink recovering means, means to deliver the ink recovered back to the means that supplies the ink, and means to supply a thinning medium to the ink recovered.
33. Ink recovering means comprising a blade, means for supporting the blade, and a pressure bar hinged to the supporting means to be raised or to be brought down toward an edge of the blade, means for holding the pressure bar down toward the blade, a chute removably mounted upon the supporting means to catch and deliver ink from said blade, and means delivering a thinning medium into said chute to mingle with the ink in the chute.
34. Ink recovering means comprising a blade, means for supporting the blade, and a pressure bar hinged to the supporting means to be raised or to be brought down toward an edge of the blade, means for holding the pressure bar down toward the blade, said supporting means comprising brackets at respective ends of the blade to which the blade is rigidly secured, a pedestal on each bracket, and a cap, means for securing said cap on the pedestal, each pedestal and its cap being adapted to embrace a fixed part of a machine, and thereby rigidly mount the recovering means on the machine for use on said machine, a projection on the inner side of the lower end of each bracket, a chute having hooks engaging over the projections, whereby it is held to catch and deliver ink from said blade, a lug on the lower end of each bracket opposite from the pedestal, a bar fixed to the lugs along across the chute, a cup mounted on the bar over the chute, and a stem on the cup extending through the bar and delivering a thinning medium from the cup down into the chute.
35. Ink recovering means comprising a blade, means for supporting the blade, and a pressure bar hinged to the supporting means to be raised or to be brought down toward an edge of the blade, means for holding the pressure bar down toward the blade, a chute removably mounted upon the supporting means to catch and deliver ink from said blade, and means delivering a thinning medium into said chute to mingle with the ink in the chute, and means for regulating the delivery of the thinning medium to the chute.
36. Ink recovering means comprising means to bear on a web and remove ink therefrom, a pressure bar supporting the web for the means to bear thereon, a flexible pressure-adjusting strip interposed between the pressure bar and the web, means near respective ends of said strip holding it to the pressure bar, and a plurality of screws passing through the pressure bar against said strip at intervals along the pressure bar and strip to variously adjust different intervals of the width of the web when the recovering means bears on the web.
37. Ink recovering means comprising a blade to bear on a web and remove ink there-

from, a pressure bar supporting the web for the blade to bear thereon, and means on said pressure bar presented toward the edge of the blade, and causing the web to travel slightly upward to the edge of the blade, to facilitate the removal of the ink from the web by the blade.

38. Ink recovering means comprising a blade to bear on a web and remove ink therefrom, a pressure bar supporting the web for the blade to bear thereon, a flexible pressure-adjusting strip on the side of the pressure bar toward the blade, means to variously adjust said pressure-adjusting strip toward the blade at various intervals therealong, a pad interposed between said

pressure-adjusting strip and the blade, and an additional strip interposed between the pressure-adjusting strip and the pad, slightly offset from and substantially parallel with the edge of the blade, whereby the pad and the web are slightly depressed alongside the blade, causing the web to travel slightly upward to the edge of the blade, to facilitate the removal of the ink from the web by the blade.
